KNITTING BALL CARRIER OR SIMILAR
ARTICLE

Max C. Meyer, Brooklyn, N. Y.

Application May 8, 1935, Serial No. 20,324

7 Claims. (Cl. 242—146)

This invention relates to improvements in knitting ball carriers or similar articles, being particularly directed to a device adapted to be carried in the hand for enclosing and carrying material of varying bulk, as, for example, knitting yarn from which thread may be unwound while being carried.

Broadly, it is an object of this invention to provide, among other things, a carrier in the form of a flexible grill or bar assembly, in substantially spherical conformation, in which yarn in the ball or like shape may be disposed for use in knitting, the carrier being adapted to be maintained in operative position while permitting withdrawal of strands of yarn, and at the same time maintaining the ball or like shape in proper confined condition through adjustability of the elements in the carrier.

Specifically, it is an object of this invention to provide a carrier for yarn balls or the like, incorporating a plurality of substantially hemispherical grill or cage-like sections interlocked with one another about a diameter to form a spherical cage-like construction, one end of the cage-like construction being rigidly assembled and the other end being adjustable to provide varying openings for insertion or removal of material therefrom, the peripheral jointure of the two hemispherical sections being adjustable and the material forming the carrier being substantially resilient.

These and other advantages, capabilities, and features of the invention will appear from the subjoined detailed description of one specific embodiment thereof illustrated in the accompanying drawing, in which

Figure 1 is a perspective view of the device.

Figure 2 is a plan view looking upwardly, of the device shown in Figure 1.

Figure 3 is a side elevation of a section of the receptacle.

Figure 4 is a partial plan view, looking downwardly, of Figure 1.

Figure 5 is a perspective view of the device with respective sections displaced.

Figure 6 is a side elevation of a section of the receptacle in expanded position.

Referring to the reference characters in the drawing, numerals 10 and 11 represent substantially hemispherical grill sections of resilient material, in this instance cellulose acetate, which originally has been wound spirally about a mandrel during an extrusion process, and which thereafter has been treated, as, for example, by compression, to provide a flattened continuous strip of resilient material having two series of convex faces 12 and 13 with respect to a vertical axis, the respective members of each series being substantially equi-distant from one another in relation to the vertical axis, thereby to form

a double-walled continuous grilled construction, the respective members of each series being parallel to one another and angularly disposed in zigzag formation with respect to the adjacent members of the other series. The flattened continuous strip thereafter is bent about a vertical axis to form a substantially semi-spherical-like grill-like double-walled construction, the free ends 14 and 15 of the strip being united by adhesion or mechanical fastening medium. 5

As shown in the dotted lines of Figure 3, two of the semi-spherical-like double-walled strips 10 and 11 are disposed one above the other with the looped edges 16 and 17 of the respective strips interposed between one another, in alternate relationship (see Figure 1), the two sections being interlocked in such relationship through the passage of a flexible and resilient thread or like element 18 through the said loops 16 and 17 and fastened at its free ends, the said resilient thread 10 serving to form the element determining the 15 circumference of the carrier being formed.

After thread 18 has been passed through the loops of the upper and lower sections 10 and 11, the assembly produced is as shown in the dotted lines in Figure 3. Thereafter, a thread 19 is passed through loops 20 at the free end of the lower section 11 and the ends thereof tied, thereby forming a predetermined restricted aperture 21 to define the base of the carrier. The elements of the section 11 upon application of the thread 19 take the position shown in full lines in Figure 3.

Through the loop 22 at the free edge of section 10 is passed a double-looped thread 23, the free end of which thread passes through looped end 25 to form an aperture for the carrier of variable diameter 26 (see Figure 4), the free end of the thread 23 being looped as at 23' to be carried on the arm or a support. After the thread 23 25 has been inserted through the loops 22 of section 10 the said section takes the configuration shown in the full lines of Figure 3, thereby providing in conjunction with section 11 for the formation of the spherical-like assembly shown in Figure 1. 45

As shown in Figure 1, a ball of wool or the like, 27, is insertable through aperture 26 of the carrier, the aperture being increased by loosening the looped thread 23 to permit insertion of the ball within the carrier, and thereafter the 50 aperture 26 is restricted in size by drawing the loop and maintaining the loop in position shown in Figures 1 and 3 by supporting the loop as at 23' upon the arm or a fixed support, the aperture 26 remaining in restricted form due to the 55 great pull on the thread 23 when the carrier is supported. As shown in Figure 1, the free end 28 of the knitting ball passes through aperture 26 for withdrawal of yarn.

As sufficient amount of yarn is withdrawn 60

through aperture 26 the diameter of the yarn ball 27 decreases, whereupon the flexible thread 18 originally under tension when the large ball has been inserted in the carrier, contracts as shown in Figure 6, from the dotted line to the full line position, thereby decreasing the diameter of the carrier, and maintaining pressure on the wool ball therein contained. As shown in Figure 5, as the wool ball decreases in size, and flexible and resilient thread 18 contracts, the grill members of the respective sections 10 and 11 have a tendency to slide towards each other at the looped ends thereof, through which thread 18 passes, particularly when the carrier, instead of being supported at the loop of thread 23, is permitted to rest on a support.

Although the material here shown is in the nature of a resilient continuous strip of cellulose acetate or like material, it is within the provision of this invention to apply continuous strips of resilient metal or non-metal, or to apply interconnected segments of such material, whether flexible or not, so long as a resilient means is provided to control the diameter of the carrier and means are provided for an expansible aperture for insertion of material into the carrier.

It is obvious that various changes and modifications may be made to the details of construction without departing from the general spirit of the invention as set forth in the appended claims.

I claim:

1. A carrier for knitting balls or similar articles, comprising a receptacle formed of flexible interlocked grill sections, each having free ends, expansible means connecting the respective grill sections and serving to control the diameter of the carrier, means for connecting the free ends of one of the grill sections to form an expansible aperture for the carrier, said last-named means serving to provide a loop for supporting the carrier, the aperture of said carrier when supported by said loop being restricted.
2. A carrier for knitting balls or the like, comprising a receptacle formed of a plurality of open ended grilled sections, each of said grilled sections being formed of a single strip of material shaped to provide looped edges, means passing through the loops of contiguous edges of said grilled sections to interlock said grilled sections therealong, said last-named means being extensible and serving to control the circumference of the receptacle, means passing through the loops of the free edge of one of said grilled sections to form a restricted aperture and extensible means passing through the loops of the free edge of the other grilled section to form an extensible aperture for said receptacle, to provide for insertion of a knitting ball or the like, said last-named extensible means being looped for disposition upon a support.
3. A carrier for knitting balls or the like, comprising a spherical-like receptacle formed of a plurality of open ended semi-spherical grilled sections, each formed of a continuous strip of material having loops defining the top and bottom edges thereof, an extensible element threaded through loops of the continuous edges of said grilled members to interlock the same

and means threaded through the loops of the free edges of the semi-spherical grilled sections to provide end apertures, the threaded means forming one of said apertures being extensible, thereby to provide for an extensible aperture. 5

4. A carrier for knitting balls or similar articles comprising a receptacle formed of a plurality of open ended semi-spherical grilled sections, each formed of a continuous length of material and having looped edges, extensible means passing through the contiguous looped edges of said grilled semi-spherical sections to interlock the same, means passing through loops of the free edge of one of said hemispherical grilled sections to form a restricted aperture and extensible means passing through the loops of the free edge of the other hemispherical grilled section to form an expansible aperture, serving to permit of expansion of said carrier, upon insertion of a knitting ball, and adapted as a knitting ball is reduced in size 20 upon withdrawal of a strand through one of the apertures to conform the receptacle to the shape of the knitting ball.

5. A carrier for knitting balls or similar articles, comprising a receptacle formed of a plurality of open ended grilled sections having looped edge formations, an extensible thread passed through contiguous edge formations of the respective semi-spherical grilled sections to form an expansible interlock between said grilled sections 30 and to provide a substantially spherical-like formation to the carrier, threading means passing through the free edge formations of the respective grilled sections to form restricted apertures, one of said last-named threading means 35 being extensible to provide an expansible aperture for insertion or removal of a knitting ball or the like.

6. A carrier for knitting balls or similar articles, comprising a receptacle formed of open ended 40 flexible semi-spherical grilled sections, said grilled sections having looped edges, extensible means passing through adjacent looped edges thereof to interlock the respective sections, and means threaded through the loops of the free edges of 45 said grilled sections for forming restricted apertures, thereby to conform the receptacle substantially to the contour of a knitting ball or similar article, the means threaded through the loops of the free edge of one of said grilled sections 50 being extensible, thereby to permit the expansion thereof for insertion and removal of a knitting ball.

7. A carrier for knitting balls or similar articles, comprising a receptacle formed of open ended 55 flexible semi-spherical grilled sections, said grilled sections having looped edges, extensible means passing through adjacent looped edges thereof to interlock the respective sections, and means passing through the loops of the free edges 60 of said grilled sections for forming restricted apertures, thereby to conform the receptacle substantially to the contour of a knitting ball or similar article, the means threaded through the loops of the free edge of one of said grilled sections 65 being extensible, thereby to permit the expansion thereof for insertion and removal of a knitting ball, said extensible means having a looped formation at the end thereof for providing a support for the receptacle. 70

MAX C. MEYER.
